UNITED STATES PATENT OFFICE

MILDRED C. MATHER, OF MINNEAPOLIS, MINNESOTA

PROTECTOR

Application filed July 14, 1928. Serial No. 292,807.

- This invention relates to a breast protector or breast covering to be worn by girls and women. The present day tendency is for women, especially the younger women and girls, to wear few clothes, especially in the summertime. The brassière or bandeaux commonly worn over the breasts is considered unnecessarily bulky by many girls who desire a lighter breast covering.
- 10 It is desirable to have some covering over the breasts when wearing thin or tight fitting clothes, so that the nipples of the breast will not project unduly, and be too prominent or unsightly. Women and girls whose 15 breasts are not greatly developed do not need any support therefor, and it is only necessary to have some means for rendering the nipple less prominent and conspicuous.
- It is an object of this invention, therefore, 20 to provide a breast covering or protector which will to a great extent obscure the nipple so that the same will not be unduly noticeable when a dress or sweater is worn.
- It is another object of the invention to 25 provide a breast covering comprising a small piece of fabric simulating a dress fabric on one side and having a waterproof surface on the other, the same being provided with adhesive to hold the same in place.
- 30 These and other objects and advantages of the invention will be fully set forth in the following description made in connection with the accompanying drawings, in which like reference characters refer to similar parts throughout the several views and in which:—
- Fig. 1 is a diagrammatic view of a bust, showing the invention in place;
- Fig. 2 is a horizontal section on line 2—2 40 of Fig. 1;
- Fig. 3 is a plan view of the device; and
- Fig. 4 is an edge view of the device.
- Referring to the drawings, the device comprises a piece of material 10. While this material might be made of various shapes, in the embodiment of the invention illustrated it is shown as substantially elliptical in shape and this form has proven to be very good in practice. The outer surface 10a of 45 fabric is preferably of silk or satin weave, simulating dress goods. The inner surface 10b is preferably water-proof and this surface can be made by providing a layer of water-proof material such as very thin rubber or as illustrated, by having a rubberized 55 surface on the fabric. Such rubberized silk or rubberized fabric is now a commercial article. The surface 10b is therefore water-proof. At each end of the device a layer of adhesive 11 is provided, which, as illustrated, is of segmental shape at the end of the 60 fabric.
- In operation the waterproof surface 10b is placed against the nipple 12 of the breast, the device being positioned centrally of the 65 nipple with the long dimension horizontally, and the same is then pressed against the breast and the adhesive portion 11 pressed firmly in contact therewith. This adhesive is of the character commonly used with adhesive surgical tape and adheres quickly 70 and securely to the skin. The device is then in position as shown in Figs. 1 and 2 and the nipple of the breast cannot project unduly. The dress or other garment of the wearer 75 will be directly in contact with the surface 10a and this surface or the fabric forming the same is preferably made flesh colored so the device will not be greatly noticeable. With the device in the position shown, a 80 dress or sweater may be worn and the breast nipples will not unduly project against the same so as to be objectionable in appearance. A comparatively smooth surface is formed 85 over the breasts by the device against which the garment engages. The device can be easily removed when desired, by simply taking hold of it and pulling the same from the skin, the adhesive 11 readily separating 90 from the skin. The device is not uncomfortable and the same will usually be worn until it is desirable to remove the same on account of soiling. The device is conveniently arranged for marketing by merely placing a piece of paper, preferably glassine, 95 over the side having the adhesive thereon. When the device is to be used, this paper is removed from the adhesive and the device can then be applied to the breasts.
- By lifting the breast somewhat before the 100

device is applied, the breast will be supported to a certain extent. One side of the device being waterproof, will prevent any moisture passing through the same to the fabric side, so that no moisture can get onto the dress or other garment worn over the device.

From the above description it is seen that applicant has provided a very simple and efficient breast covering. The same is easily made and may be inexpensively produced, and thus sold at a very reasonable price. The device is easily and quickly placed in position for use. The small amount of adhesive used on the device eliminates any unhealthful action. It has become the practice of some girls to simply cut up adhesive tape and place the same over the breasts. The entire surface of this tape is covered with adhesive, however, and it has been found that the same is injurious when covering such a large area and extending over the nipples. With the present invention very little of the skin surface is engaged by the adhesive and there is no covering directly over the nipples closing the same or preventing circulation of air. The device can thus be worn without any injurious effects. The device has been amply demonstrated in practice, found to be very successful, and is being commercially made.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

40. What is claimed is:—

1. A breast covering comprising an elongated piece of thin fabric having at least one side thereof water-proofed, the water-proofed side of the fabric being inward and having adhesive at the end portions thereof adapted to engage the breasts at either side of the nipple and hold the device in place.

2. A breast covering comprising a thin fabric sheet of general oblong shape and adapted to extend over the nipple of the breast and portions at opposite sides thereof, adhesive material only adjacent the ends of said sheet for engaging the skin at each side of the nipple to hold the device in place, the portion over the nipple being free of adhesive and adapted to hold the end of the nipple in the line of a circle touching the breast at each side thereof.

60. In testimony whereof I affix my signature.
MILDRED C. MATHER.
